FIG. 2.

FIG. 1.

FIG. 3.

FIG. 1 is a side elevational view of a radio, showing my new design with the earphone and grounding clamp in perspective and the conductors partly broken away to indicate indeterminate length, the opposite side being substantially a mirror image thereof;

FIG. 2 is a top end view with the earphone and grounding clamp being omitted for convenience in illustration; and

FIG. 3 is a bottom plan view with the earphone and grounding clamp being omitted for convenience in illustration.

I claim:

The ornamental design for a radio, substantially as shown and described.
